COUNTER OR TABLE DISPENSING AND
DISPLAY CONSTRUCTION

Bertram J. Goldsmith, Neshanic, N. J.

Application May 24, 1938, Serial No. 209,719

8 Claims. (Cl. 206—77)

This invention relates to counter or table dispensing and display constructions and in its more specific aspects is concerned with means for displaying and dispensing ribbons, bindings, 5 tapes and other narrow fabrics.

One object of the invention is to provide an improved counter-well construction and more specifically to provide a counter-well constructed and arranged in such a way as to facilitate the dispensing of the material therefrom and to improve the display of such material in the well.

Another object of the invention is the provision of counter compartments or wells of the type which are constituted in part by vertical partition walls, the construction and arrangement being such as to obviate the necessity for the blocks heretofore utilized for retaining said compartment walls in vertical position and in compartment defining relation.

20 A further object of the invention is generally to provide improved means such as store counter wells or compartments for facilitating and improving the dispensing and display of ribbons or other narrow fabrics.

25 The above objects of the invention and other objects which might hereinafter appear will be fully understood from the following descriptions considered in reference to the accompanying drawing.

30 In the drawing:

Fig. 1 is a perspective view of part of a counter display embodying the present invention;

Fig. 2 is a perspective view of one of the counter wells, parts being removed for the sake of clearness of illustration;

Fig. 3 is a sectional view on the line 3—3 of Fig. 2;

Fig. 4 is a detail sectional view on the line 4—4 of Fig. 2;

40 Referring now more particularly to the drawing, the dispensing and display construction embodying the present invention comprises, as here shown, a suitable support 10 such as, for example, a store counter or table upon which the compartment or well defining partition walls 12 are, as is customary, disposed in vertical position.

In accordance with the present invention, the wooden blocks heretofore usually utilized for supporting the compartment defining walls in vertical position are preferably eliminated, and in addition, provision is made for subdividing each compartment or counter well into sub-compartments, one of the latter in each well constituting a supply chamber for the material in the well, and another of said sub-compartments constitut-

ing a display chamber for the material to be dispensed therefrom. For this purpose there is utilized in accordance with the preferred form of the invention illustrated herein, table members 14, one of which is removably positioned in each 5 of the counter wells. As each of the members 14 positioned within said wells is preferably of the same construction, only one will be described. Each table member 14 comprises a top 16 of rectangular, here shown as square outline, and provided at each of its four corners with a leg 18. Each of said members 14 may be made of any suitable material; preferably it is made of sheet metal, and in that case legs 18 may be formed integral with top 16 and are preferably of angle-iron shape, having sides 20 and 22 disposed at right angles to each other. It will be understood the vertical wall 12 which defines the compartment or wells are engaged by members 14 whereby the latter serve to retain said members in vertical upright position, although it is within the scope of the present invention to provide other means for retaining said vertical walls in upright position. Each table 14 may be made in 10 one piece of material other than metal, for example it may be molded from "Bakelite" or any other suitable synthetic resin or it may be made of wood or wood pulp.

As clearly shown in the drawing, the top 16 of the table 14 is disposed a substantial distance 30 below the upper edges of vertical walls 12 as well as a substantial distance above the top of the counter well or table 10 and is supported in said position by legs 18 which are dimensioned accordingly. Preferably, wall 16 is about mid-way between the top and the bottom of the compartment. Said table top forms together with the companion vertical walls of its companion compartment a supply chamber 24 and a display chamber 26. The material to be dispensed from 35 each compartment is housed within supply chamber 24 below wall 16.

As here shown, said material is in the form of a spool or winding of ribbon 28 mounted preferably in horizontal position, that is resting on one 40 of the spool flanges 30. The ribbon or other narrow fabric or other material extends from the supply chamber 24 through an opening 32 in table top 16 to display chamber 26. It will be understood that a suitable quantity of said material 45 will be displayed, in the use of the invention, in said display chamber where the material will rest upon table top 16 which thus constitutes the bottom of said display chamber. A guide pin 33 may be provided, as here shown, for guiding the ribbon 50

from the spool to opening 32. Said guide pin is preferably a roller pivoted at its ends 34 and 36 in leg 18 adjacent opening 32 and in a part 38 struck out and downwardly from table top 16.

5 Provision is made for permitting rotation of spool 28 in supply chamber 24. For this purpose, there is provided, as here shown, a vertically disposed pin 40 which is secured to and depends from wall 14, preferably centrally of the latter, 10 for engagement with spool 28 in its central opening 42 whereby said spool is mounted for rotation in a fixed path about said pin. For convenience in inserting or removing member 14 into and out of the well, table top 16 is provided with a finger 15 opening 44.

While I have shown and described the preferred embodiment of my invention, it will be understood that the latter may be embodied otherwise than as here shown, and that in the illustrated embodiment certain changes in the construction and arrangement of parts may be made and that certain parts not essential to the broad function of the construction and arrangement may be omitted. Thus, for example and without 20 indicating all of the changes which may be resorted to in practicing the present invention, it may be stated that table 14 can be made with attached instead of integral leg portions and that the opening for the passage of the ribbon from 25 the supply chamber to the display chamber may be formed otherwise than as here shown, for example, as a notch in edge portion of the table top or by spacing an edge of said top from the adjacent vertical compartment defining wall. 30 Other changes in the details of construction and arrangement of parts may be made and will occur to those skilled in the art particularly in view of the present disclosure.

Therefore, I do not wish to be limited precisely 40 to the invention as herein shown or described except as may be required by the appended claims.

Having thus described my invention, what I claim and desire to secure by Letters Patent is:

1. In a dispensing and display construction and 45 arrangement of the character described, means comprising vertical walls defining a compartment for the supply and display of material, and a table member disposed within said compartment, said table member having a top disposed above the bottom of said compartment and below the upper edges of said walls forming a lower supply chamber and an upper display chamber, there being an opening for the passage of material from said supply chamber below said 50 table top to said display chamber above said table top, and legs fixed to said table top for supporting the latter in position above the material in said supply chamber.

2. In a dispensing and display construction and 60 arrangement of the character described, means comprising vertical walls defining a compartment for the supply and display of material, and a table member disposed within said compartment, said table member having a top disposed above the bottom of said compartment and below the upper edges of said walls forming a lower supply chamber and an upper display chamber, there being an opening for the passage of material from said supply chamber below said table top to said 65 display chamber above said table top, and legs fixed to said table top for supporting the latter in position above the material in said supply chamber, said table top having means depending therefrom adapted to project into an opening of 70 a spool or winding of the material in said supply

chamber whereby said winding is guided for rotation to permit unwinding of the material therefrom for transferring the same from said supply chamber to said dispensing chamber.

3. In a dispensing and display construction and 5 arrangement of the character described, means comprising vertical walls defining a compartment for the supply and display of material, and a table member disposed within said compartment, said table member having a top disposed above the bottom of said compartment and below the upper edges of said walls forming a lower supply chamber and an upper display chamber, there being an opening for the passage of material from said supply chamber below said table top to said 10 display chamber above said table top, and legs fixed to said table top for supporting the latter in position above the material in said supply chamber, said table top having means depending therefrom adapted to project into an opening of 15 a spool or winding of the material in said supply chamber whereby said winding is guided for rotation to permit unwinding of the material therefrom for transferring the same from said supply chamber to said dispensing chamber, and means 20 carried by said table top for guiding said material from said winding for passage through said opening.

4. In a dispensing and display construction and arrangement which comprises a counter or 30 other support and a plurality of adjacent compartments defined by vertical walls, a table member disposed within each of said compartments, said table member having a top disposed above the bottom of said compartment and below the upper edges of said vertical walls forming a lower supply chamber and an upper display chamber, there being an opening for the passage of material from said supply chamber below said table top to said display chamber above said table top, and legs fixed to said table top for supporting the latter in position above the material in said supply chamber, the table members in adjacent compartments constituting means to hold said 35 walls in vertical position.

5. In a dispensing and display construction and arrangement which comprises a counter or other support and a plurality of adjacent compartments defined by vertical walls, a table member disposed within each of said compartments, said table member having a top disposed above the bottom of said compartment and below the upper edges of said vertical walls forming a lower supply chamber and an upper display chamber, there being an opening for the passage of material from said supply chamber below said table top to said display chamber above said table top, and corner legs integral with said table tops and engaging said walls in the corners of said compartments for holding said walls in vertical position.

6. In a dispensing and display construction and arrangement which comprises a counter or other support and a plurality of adjacent compartments defined by vertical walls, a table member removably disposed within each of said compartments, said table member having a top disposed above the bottom of said compartment and below the upper edges of said vertical walls forming a lower supply chamber and an upper display chamber, there being an opening for the passage of material from said supply chamber below said table top to said display chamber above said table top, and legs fixed to said table top for supporting the latter in position above the 70 material in said supply chamber.

material in said supply chamber, the table members in adjacent compartment constituting means to hold said walls in vertical position.

7. In a dispensing and display construction and arrangement of the character described, means comprising vertical walls defining a compartment for the supply and display of material, and a table member removably disposed within said compartment in engagement with said walls, 5 said table member having a top disposed above the bottom of said compartment and below the upper edges of said walls forming a lower supply chamber and an upper display chamber, there being an opening for the passage of material from said 10 supply chamber below said table top to said display chamber above said table top, and legs fixed to said table top for supporting the latter in position above the material in said supply chamber.

20 8. In a dispensing and display construction and arrangement of the character described, means comprising vertical walls defining a com-

partment for the supply and display of material, and a table member removably disposed within said compartment in engagement with said walls, said table member having a top disposed about the bottom of said compartment and 5 below the upper edges of said walls forming a lower supply chamber and an upper display chamber, there being an opening for the passage of material from said supply chamber below said table top to said display chamber above 10 said table top, and legs fixed to said table top for supporting the latter in position above the material in said supply chamber, said table top having means depending therefrom adapted to project into an opening of a spool or winding of 15 the material in said supply chamber whereby said winding is guided for rotation to permit unwinding of the material therefrom for transferring the same from said supply chamber to said dispensing chamber. 20
